RAILROAD CROSSING AND FROG

Edwin W. Goodaire and George Arnold, Shaker Heights, Ohio, assignors to Cleveland Frog and Crossing Company, Cleveland, Ohio, a partnership composed of George C. Lucas and George W. Balkwill

Application July 5, 1932, Serial No. 620,832

3 Claims. (Cl. 246—460)

This invention relates to railway track construction and especially to crossings, frogs, and similar track structures.

The object of the invention is to provide in a railway crossing, frog, or similar track structure at the point thereof subject to the greatest wear, an insert formed of a special hardened steel alloy and permanently incorporated in the structure.

10 A further object is to provide a railway crossing, frog, or similar track structure having an insert incorporated therein, as specified above, wherein the insert and the portion of the structure receiving the same are so constructed that 15 the insert will be held effectively against a tendency to rotate because of wheel impacts, will not rock or wabble as wheels pass thereover, and will be securely mounted in the structure against displacement in any direction.

20 A still further object is to provide a railway crossing, frog, or similar track structure having an insert, as specified hereinabove, so constructed that it may be readily, economically, and accurately formed by a combination of forging, machining, and/or grinding operations.

Further and additional objects and advantages residing in the invention will become more apparent hereinafter during the following detailed description of an embodiment of the invention 30 which is illustrated in the accompanying drawing, wherein

Fig. 1 is a top plan view of a one quarter railroad crossing embodying the present invention, the crossing being shown connected to certain of the ordinary track rails.

35 Fig. 2 is a top plan view similar to Fig. 1 with the insert and track rails omitted.

Figs. 3, 4 and 5 are sectional views taken substantially on lines 3—3, 4—4 and 5—5, respectively, of Fig. 1, looking in the direction of the arrows, and

Fig. 6 is a diagrammatic view of a crossing showing how the one quarter crossings of Fig. 1 are used.

45 The present invention contemplates the provision of means in a railroad crossing, frog, or similar track structure that will obviate the chief difficulty heretofore found to exist in such structures, namely the breaking down and wearing 50 away of the structure at the intersection of the flangeways because of the severe blows imparted thereto at such point by the wheels of the cars.

The one quarter crossing illustrated in the accompanying drawing and constituting an embodiment of the invention comprises an integral

casting A and an insert B. The casting A usually formed of manganese steel, includes a main base or bed portion 10 from which extend in the desired angular relationship, the connecting arms 11. It will be understood that for each pair of intersecting tracks four of the castings A will be employed as indicated in Fig. 6.

The connecting arms 11 include heads 12 and guards 13 between which are arranged the grooves or flangeways 14 for the wheel flanges. 65 The connecting arms 11 connect each casting of the crossing to the track rails and to the other castings. The construction just referred to is conventional and need not be set forth in greater detail.

The base or bed portion 10 of the casting A is provided at its upper side with a recess or chamber 15 (see Fig. 2) preferably, but not necessarily, circular in shape to facilitate grinding and/or machining the surfaces thereof, the bottom wall 16 of said chamber having formed centrally therein a non-circular opening 17 (shown in this instance as square in shape), the upper end of which is somewhat larger than the lower end to provide a shoulder or ledge 18. The side wall of the recess or chamber 15 is provided with an annular undercut or diagonal recess 19 and with a plurality of recesses or grooves 20 communicating therewith and extending upwardly to the top edge of the casting, such recess or groove 19 being connected to the shoulder 18 by means of recesses or grooves 21 formed in the bottom wall 16 of the chamber 15. The walls of the chamber, particularly the bottom wall thereof, and the walls of the opening 17 with its shoulder 18 are machined and/or ground to enable the insert, now to be described, to snugly fit therein and be free of any tendency to wabble or rock.

90 As previously stated, it is proposed to employ with the casting A an insert B constituting the intersection of the flangeways of the crossing and formed of a special forged alloy steel heat treated to a definite predetermined hardness to withstand the blows of the wheels. The insert will be of the same general configuration as the chamber 17 and will have a snug fit therein rather than a driving fit, the insert being machined and/or ground and resting at its inner end on the ground surface 16. The inner end of the insert is provided with a non-circular portion 22 corresponding in shape to the opening 17 in the bottom wall of the chamber 15 and fitting therein to positively maintain the insert against rotation in the chamber.

100

105

110

The insert is also provided with an annular recess 23 arranged to cooperate with the recess 19 when the insert B is fitted in the chamber to form an annular channel for a purpose later to be referred to. The upper surface of the insert will have formed therein intersecting grooves or flangeways 24 aligning with the grooves or flangeways 14 in the casting A.

The insert B is positioned in the chamber 15 of the casting A with the non-circular portion 22 thereof extending into the opening 17 in the bottom wall of the chamber, the upper surface of the insert being flush with the heads 12 and guards 13 of the casting A, while the grooves or flangeways 24 connect the grooves or flangeways 14.

In order to securely and permanently fasten the insert B in the chamber of the casting A suitable spelter, indicated in Figs. 3 and 4 at 25, is poured in the molten state into the upper ends of the recesses or grooves 20 so that it will flow into and fill the annular channel formed by the recesses or grooves 19 and 23 and will further flow through the recesses or grooves 21 and fill 25 the space between the insert B, the shoulder or ledge 18 and the wall of the opening 17 in the casting A. In order to permit the escape of air and gases trapped in the recesses or grooves by the incoming spelter one or more suitable vents 30 to the atmosphere are provided, as indicated at 26 in Fig. 3. When the spelter, filling the annular channel formed by the recesses or grooves 19 and 23, the space between the insert and shoulder 18 and the grooves or recesses 20 and 35 21, hardens it will be noted that the insert will be securely locked or keyed in the casting and will, in effect, be a permanent part of the crossing structure, especially since the grooves 19 and 23 are so arranged that the hardened spelter will 40 form a diagonal key which must be compressed and sheared before the insert can be removed from the chamber.

In crossings, frogs, and similar track structures, the points thereof subject to the greatest 45 wear lie at the intersection of the flangeways for the wheel flanges with the result that at such points they rapidly wear away and render the entire structures unfit for use although the remainder thereof may not be materially worn. 50 However, such worn crossings, frogs, or similar track structures must be replaced and the cost of track maintenance is therefore considered high.

It will be seen that the present invention enables the major portion of the crossing, frog, or other track structure to be a casting formed of a material that is sufficiently wear resisting for the purposes required and which is not prohibitive in price, such as manganese steel, while the portion 55 of the structure including the intersection of the flangeways can be a forging formed of a special steel alloy heat treated to a predetermined hardness, such that because of its density it will have maximum impact resisting characteristics and will stand up in use at least as long as the major portion of the structure. The original cost 60 of a structure thus constructed will compare favorably with the cost of the ordinarily formed similar structure with the advantage that its life 65 will greatly exceed the older forms of structures.

Since the chamber in the casting and the insert have their surfaces machined and/or ground, the insert will possess stability and will not rock or wobble in use, while the non-circular inner end 70 75 of the insert fitting within the non-circular open-

ing in the bottom of the chamber in the casting will positively maintain the insert against rotative movement. The insert will be permanently incorporated into the structure by the spelter heretofore referred to.

80

The wheels of railway cars develop in use what is generally known as a "false flange" adjacent the edge of their periphery opposite to the regular flange, that is, the peripheral portion of the wheels in contact with the rail heads develops an annular groove or depression due to wear, while the peripheral portion adjacent the outer side of the wheels does not wear because it is not in contact with the rail heads. This "false flange" exerts a substantial wearing effect upon crossings, frogs, or other track structures, especially at the intersection of the flangeways of the structures. The present invention possesses the advantage of substantially reducing or practically eliminating the forming of depressions at the intersection of the flangeways as are now occasioned by the "false flange" of wheels passing over the crossings, frogs, or other similar track structures.

85

90

95

It will be understood that, although the casting forming the quarter crossing has been illustrated as having its arms arranged at right angles with respect to each other, such angular arrangement is often varied, depending upon the angle of the crossing and that there is no intention to limit the present invention to a right angle crossing.

100

Although a preferred embodiment of the invention has been illustrated and described herein, it should be understood that the invention is 110 susceptible of various modifications and adaptations within the scope of the appended claims.

105

Having thus described our invention we claim:

1. A railway crossing frog or similar track structure, comprising a casting having an upwardly facing circular chamber therein at the intersection of the flangeways of the structure, said chamber having ground and/or machined side and bottom walls and being provided at its bottom with a non-circular downwardly extending opening, an insert of denser and harder metal than said casting interfitting said chamber and having ground and/or machined surfaces directly engaging the walls thereof and being provided with a non-circular portion fitting the said 120 non-circular opening with a metal to metal contact to maintain said casting and insert against relative rotation, and means securing said insert in said chamber.

115

2. A railway crossing frog or similar track 130 structure, comprising a casting having an upwardly facing chamber therein at the intersection of the flangeways of the structure, said chamber having ground and/or machined side and bottom walls and being provided in its side 135 wall with a perimetrical undercut groove and in its bottom wall with a non-circular downwardly extending opening, an insert of denser and harder metal than said casting interfitting said chamber and having ground and/or machined surfaces 140 directly engaging the walls thereof and being provided with a peripheral undercut groove and with a non-circular portion accurately fitting the said non-circular opening, said grooves cooperating to form a substantially continuous passageway surrounding the insert and diagonally intersecting the line of contact between said insert and the side of said chamber, and spelter arranged in said passageway and forming a key 145 permanently securing said insert in said chamber.

150

3. A railway crossing frog or similar track structure comprising a casting having an upwardly facing circular chamber therein at the intersection of the flangeways of the structure, 5 said chamber having ground and/or machined side and bottom walls and being provided at its bottom with a non-circular opening having a peripheral shoulder at its upper end, the side wall of said chamber having a perimetrical groove 10 therein and an upwardly extending groove communicating therewith, the bottom wall of said chamber being provided with a groove communicating with said perimetrical groove and with said peripheral shoulder, an insert of denser 15 and harder metal than said casting interfitting
